UNITED STATES PATENT OFFICE.

ALFRED GUIDRY, OF COMFORT, TEXAS.

AUTOMATIC DOOR-OPERATING DEVICE.

Application filed May 21, 1923. Serial No. 640,493.

To all whom it may concern:

Be it known that I, ALFRED GUIDRY, a citizen of the United States, residing at Comfort, in the county of Kendall and State 5 of Texas, have invented new and useful Improvements in Automatic Door-Operating Devices, of which the following is a specification.

This invention contemplates the provision 10 of an automatic door operating mechanism, primarily intended for use with garages, barns or the like, the mechanism being actuated by the weight of the vehicle, as the latter approaches the door opening, whereupon 15 the doors are automatically opened and subsequently closed when the mechanism is relieved of the weight of the vehicle.

The nature and advantages of the invention will be better understood when the following 20 detailed description is read in connection with the accompanying drawings, the invention residing in the construction, combination and arrangement of parts as claimed.

In the drawings forming part of this application, like numerals of reference indicate similar parts in the several views, and wherein:

Figure 1 is a view of the mechanism showing 30 the arrangement of parts with the door of the garage closed.

Figure 2 is a similar view showing the arrangement of parts with the doors opened.

Figure 3 is a sectional view taken on the 35 line 3—3 of Figure 1.

Figure 4 is a sectional view taken on the line 4—4 of Figure 2.

Figure 5 is a section on line 5—5 of Fig. 1.

Referring to the drawings in detail, A indicates a garage, barn or the like equipped with sliding doors B, the latter being hung from suitable tracks C in the usual well known manner, the mechanism for automatically 40 opening and closing these doors essentially embodies horizontally disposed rack bars 10 which slide through suitable frame like guides 11 mounted on posts 12. There is one of these bars 10 for each door, and the adjacent ends of these bars are connected 45 with the respective doors so that the doors are opened and closed simultaneously as the rack bars are reciprocated in a manner to be presently described. It will be noted that the posts 12 are arranged a proper distance 50 in advance of the garage and also beyond

the sides thereof, the doors passing between the garage and said posts when they are moved to an open position. The mechanism for each door is exactly the same and illustrated in the drawings. For instance each 60 rack bar 10 meshes with a large gear 13 which is also journaled upon the frame like guide member 11, and the diameter of this gear is such that it completely opens the 65 door upon one revolution of the gear. Carried by the gear 13 is a small pinion 14, the latter meshing with a vertically disposed rack bar 15, which operates to rotate the gear 13 for the purpose specified. The rack 70 bars 15 for the respective doors have their lower extremities associated with a floating shaft 16, the latter being suspended by coiled springs 17 which in turn are connected with the frame like members 11. There are preferably 75 two of such springs connected with each frame member, and the said springs function to hold the shaft 16 elevated an appreciable distance above the ground. The shaft 16 is lowered against the tension of 80 these springs 17 by the weight of the vehicle, and as the shaft is depressed, it passes between suitable guides 18. That portion of the shaft which pass between these guides is 85 equipped with rollers 19 to minimize friction.

This shaft 16 is arranged between and connected with a pair of normally inclined platforms 20 and 21 respectively, each of which is hingedly connected as at 22 to a beam 23 embedded in the ground. The platforms are connected with the shaft 16 by means of bars 24 which project from one end of the platform and pass over rollers 25 carried by the shaft. These bars 24 are 90 crossed, so that both platforms 20 and 21 are simultaneously depressed together with the shaft 16 when the vehicle passes over either of the platforms. It is of course, to be understood that the platform 20 is arranged exteriorly of the garage, while the platform 21 is arranged interiorly thereof. By this arrangement the doors are automatically 95 opened when the vehicle approaches the garage, or as the vehicle moves in the direction of the door when leaving the garage. However, after the vehicle has passed over the platforms, both of which assume a substantially horizontal position, as the vehicle passes through the door opening, the springs 17 which have been tensioned incident to the depression of the shaft 16 100 105 110

function to automatically close the doors. The garage, barn or the like must of necessity be equipped with an auxiliary door, by means of which access may be had to the garage independently of the main doors inasmuch as the latter cannot be actuated by the weight of a man, the springs 17 being very strong to automatically close the doors and hold the platforms and other component parts of the mechanism normally in the position shown in Figure 1.

While it is believed that from the foregoing description, the nature and advantages of the invention will be readily apparent, I desire to have it understood that I do not limit myself to what is herein shown and described and that such changes may be resorted to when desired as fall within the scope of what is claimed.

Having thus described the invention, I claim:

1. The combination with a pair of sliding doors, of rack bars secured to said doors and mounted for sliding movements toward and away from each other, vehicle actuated means for simultaneously moving said bars in directions to automatically open the doors, said means including vertically disposed rack bars, gears rotated by the latter mentioned rack bars and meshing with the

first mentioned rack bars to actuate the latter, yieldable means for normally holding the vertical bars elevated and the doors closed, a shaft connecting said vertical rack bars, and platforms arranged at opposite sides of the shaft and connected therewith to move the latter and the vertical rack bars downwardly under the weight of the vehicle incidentally to the opening of said doors as described. 35

2. The combination with a pair of sliding doors, of rack bars secured to said doors and mounted for sliding movement toward and away from each other, vertically disposed rack bars, gears adapted to be rotated by the last mentioned rack bars, and meshing with the first mentioned rack bars to actuate the latter, and vehicle actuated means for simultaneously operating the vertical rack bars to automatically open the doors, said means including a depressible platform, springs suspended from said vertical rack bars, and a floating shaft supported by said springs and connected with said platforms, whereby the vertical bars are lowered when the platform is depressed to automatically open the doors. 45 50

In testimony whereof I affix my signature.

ALFRED GUIDRY.
